CLAIM

Related U.S. Application Data

I claim the ornamental design for an elevating support for the head of a bed structure for the treatment of reflex esophagus, as shown and described.

DESCRIPTION

(63) Continuation-in-part of application No. 29/095,272, filed on Oct. 20, 1998, now abandoned.

FIG. 1 is an upper perspective view of an elevating support for the head of a bed structure for the treatment of reflex esophagus;

(51) **LOC (7) Cl. 08-05**

FIG. 2 is a lower perspective view thereof;

(52) **U.S. Cl. D8/374**

FIG. 3 is a top plan view thereof;

(58) **Field of Search D8/374, 375, 400,**

FIG. 4 is a bottom plan view thereof; and,

D8/499, 402; 5/509.1, 658, 663; 248/188.2,

FIG. 5 is a side elevational view thereof, all side elevational views being identical.

346.11; 16/32, 19

The typical dimensions for the design of this invention are that the body portion thereof is 7½ inches tall and is 5 inches square thus making its sides 7½ inches tall and 5 inches wide. The body portion has a cylindrical opening in its top which is 4 inches in diameter and 1 inch deep. The bottom portion of the body portion has a cylindrical opening which is 4 inches in diameter and 5 inches deep. The two cylindrical openings are separated by a horizontal panel which is 1½ inches in vertical thickness. Both openings are centered on a center vertical axis of the body portion.
